UNITED STATES PATENT OFFICE.

LOUIS ISIDORE HENRY, OF TOULON, FRANCE.

AUTOMATIC STABILIZING APPARATUS.

1,335,893.

Specification of Letters Patent.

Patented Apr. 6, 1920.

Application filed February 27, 1919. Serial No. 279,663.

To all whom it may concern:

Be it known that I, LOUIS ISIDORE HENRY, a citizen of the French Republic, residing at Toulon, France, have invented certain new and useful Improvements in Automatic Stabilizing Apparatus, of which the following is a specification.

This invention relates to automatic stabilizing devices for use in connection with all vehicles which move in fluids such as air (aeroplanes), water (submarines), air and water (vessels plying on the surface of the water). In the following description the general term "vessel" will be used to indicate any one of these vehicles.

When the fluid through which the vessel is traveling is agitated, the vessel under way is subjected to oscillatory movements of pitching and rolling about a certain mean position. The result of these movements, by reason of the automatic operation of the stabilizing device which forms the subject of the present invention, is to set in operation auxiliary surfaces or blades, whose resistance to the fluid, by reason of the speed of travel of the vessel, counteracts the pitching and rolling movements of the vessel and restores its equilibrium. Since, in order that the blades enter into action, it is necessary that the oscillatory movements be started, these latter must not be completely suppressed, but must be rapidly moderated and restricted in such manner that their amplitude is confined within narrow limits.

This automatic stabilizing device comprises a member termed a "vertical member" which is a pendulum constructed and suspended so as to remain vertical, or in a fixed position near the vertical, whatever be the movement of its point of suspension due to the travel and oscillations of the vessel, this vertical member maintaining a fixed direction in space with respect to the horizontal plane. The vessel in its oscillations moves with respect thereto, or reversely if it is considered that the vertical member oscillates irregularly with respect to the vessel about its point of suspension. These movements of the vertical member with respect to the vessel are utilized to act on shafts rigidly attached to the vessel, which set in action the blades provided to counteract the pitching and rolling movements of the vessel. As a matter of fact the pendulum or vertical member is too sensitive to control these elements directly without deranging the equi-

librium of the vessel. To remedy this there is interposed between the pendulum and the elements controlling the blades an intermediate element termed the "stabilizer," which is likewise a pendulum connected to the main pendulum by an auxiliary device so as to follow exactly all movements with respect to the vessel, and itself actuating the control elements of the blades. The reactions of these elements on the stabilizer are balanced by compressed air, which is the medium of service between the stabilizer and the pendulum, and none of these reactions are transmitted to the latter.

An embodiment of this invention, by way of example, is described hereinafter and represented in the accompanying drawings in which:

Figure 1 is a side view, partly in section, of the entire device with certain parts broken away for the purpose of clearness.

Figs. 2 to 5 show one of the two similar elements intended to serve the pendulum stabilizer, called stabilizing cylinders, Fig. 2 being a sectional elevation, Fig. 3 a plan, Figs. 4 and 5 an elevation and plan.

Fig. 6 represents one of the two false stabilizing cylinders intended to overcome the effects of inertia of the slides of the true stabilizing cylinders on the pendulum.

Fig. 7 represents a mechanism for connecting and rendering immovable the pendulum and the stabilizing device from each other and from the vessel.

Fig. 8 is a diagram of the connection of the device with the motors of the blades, for clutching and releasing them.

The pendulum proper or vertical member is a solid of revolution, not capable of being changed in form, and consists of the parts referred to hereinafter.

A member 1 in the form of an extremely elongated bell, supporting a ring 2 by means of arms 1¹, is suspended from a hollow rod 3 terminating in a weight 4 the height of which on rod 3 may be regulated by means of screw threads. This pendulum is provided, interiorly at its upper end, with a suspension pivot whose point is at 5. The center of gravity of the pendulum is adjusted so as to be exactly at 5. It may be brought there with great exactitude by regulating the height of the mass 4, and by the radial displacement on the latter of small masses 4¹ 110 which it carries.

By means of its pivot the pendulum rests

on a hollow rod 6 which is rigidly attached at its lower end to a surface of the vessel, shown diagrammatically at 7 in Fig. 1. This rod 6 is, for example, vertical in normal travel of the vessel on calm fluids (this condition is not absolute and a change of position of the vessel does not influence the operation of the device) and the rod 6 terminates at its upper portion in a socket in which the point of the pivot 5 rests. This socket is seated in a semi-spherical head 8 having the point 5 as a center. To the upper part 1 of the bell there is screwed a lower part 1² provided interiorly with a semi-spherical bearing surface forming a snug fitting ball and socket joint with the head 8. Part 1² is provided with a toothed crown 1³ actuated by a worm 1⁴ carried by a bearing arm fixed to the upper part 1, 20 and manipulated by a wheel 1⁵. Another arm 1⁶ of the part 1, located opposite the first, carries two rollers 1⁷ which travel in upper and lower grooves of the toothed crown 1³ to guide members 1 and 1¹ with respect to each other. The wheel 1⁵ rotates with the member 1² and moves vertically with respect thereto by sliding vertically on pins 1⁸ carried by the member 1².

Compressed air from any suitable source 30 passes through the tube 6 into the hollow rod 3 of the pendulum. The joint formed at the head 8 allows only a minute leakage of air at this point and the air passes through tubes 6 and 3 at a greater pressure than that for which it is utilized.

Another tube 9 surrounds the hollow rod 6 and terminates at the top in a set of tubes 10 which direct compressed air against a suitable surface located within the base of bell 1. The plane of this set of tubes is perpendicular to the axis of the rod 6, that is, horizontal when the latter is vertical in the normal position of the vessel traveling on calm fluids. The set of tubes comprises 45 blowing nozzles which are similar and uniformly distributed, to form a crown which directs a continuous and uniform blast of air over the entire inner circumference of the base of the pendulum 1.

50 The stabilizer or member intermediate the pendulum and the control elements of the ailerons for stabilization of the vessel include the chief elements hereinafter described. It consists (Fig. 1) of a bell 12, ballasted at the bottom by a weight ring 13 surmounted by a tubular rod 14 which surrounds the rod 3 of the pendulum, and carries at its upper part a weight 15 whose height on the rod may be regulated by 55 means of screw threads. This stabilizer has a semi-spherical surface 17 resting on balls 18, mounted on another semi-spherical surface 16 forming part of the pendulum 1.

60 The two surfaces 16 and 17 also have their centers at 5. The center of gravity of the

stabilizer is also at the point of suspension 5, being brought there with great accuracy by regulation of the height of the weight 15 and by the radial movement thereon of small masses 15¹, which it carries.

70 Two stabilizing cylinders 28, which will be described hereinafter, are located in two perpendicular planes passing through the axis of tube 6. One of them is shown diagrammatically at 19. It may rotate about 75 its axis (a—a) which itself may rotate about axis (b—b), which is arranged at right angles to (a—a), and extends parallel to the axis of tube 6. This axis (b—b) moves with the vessel during pitching and rolling 80 of the vessel.

85 Referring to Figs. 2, 3 and 5, it will be seen that each stabilizing cylinder 28 has a slide 39 for distributing compressed air to the interior of the cylinder and on opposite sides of a piston 27, which is slidably mounted within the cylinder. This slide has a hollow rod 38 terminating in a fork 38¹, the arms of which are pivotally connected with pins 20 fixed to an oscillatable 90 and slidable sleeve 31 carried by the hollow rod 3. As shown in Fig. 3, the hollow rod 3 is provided with a plurality of holes which permit compressed air from the interior of the rod to pass into an annular 95 chamber 32 of the sleeve 31. From this chamber the air is conveyed by pipes 33 to the interior of the hollow slide rod 38.

100 The piston 27 is controlled by the slide 39 and is rigidly connected by tube 34 and arms 34¹ to pins 20¹ fixed to a sleeve 36, which turns and slides on the tube 14 of the stabilizer. When the axes of tubes 3 and 14 coincide the axes of pins 20 and 20¹ are coaxial.

105 The corresponding elements of the second stabilizing cylinder (not shown), the axis of which is in the median plane perpendicular to the plane of Fig. 1, are connected to the rod 3 of the pendulum by pins 21, and to the rod 14 of the stabilizer by pins 22, which also have the same axis as pins 21 when the axes of tubes 3 and 14 coincide. The stabilizer, caused by the reactions of the blade control elements to assume rotary 110 movements about point 5, would entrain therewith in these movements the pistons connected to it. However, none of these movements take place, and the pistons have no other movements than those of the slides 115 connected to the pendulum and which they accompany constantly, and that because the momentums with respect to point 5 of the reactions of the elements for controlling the ailerons (blades) are balanced by the 120 force of the compressed air on the pistons, transmitted through the latter to the stabilizer.

125 The bell 12 of the stabilizer has a certain number of toothed arcs such as 23—24, (this 130

number varies accordingly as it is desired to operate for longitudinal stabilization only, or for lateral stabilization only, or for both simultaneously, or whether only one or two governors or blades are used for each of these stabilizations) engaging with pinions 25 whose axes are connected to the surfaces of the vessel shown diagrammatically at 26. The toothed arcs 23, 24 are mounted and 10 rotate on horizontal axes 23¹, 24¹, which pass through the point of suspension 5. The arcs formed by the teeth of the parts 23—24 have said point 5 as a center and are concentric with the semi-spherical surface 8. 15 By means of suitable connections, pinions 25 actuate the control slides of the motors which manipulate the stabilization surfaces or ailerons. These pinions 25 have a flange at each side as shown in Fig. 8 to engage 20 the toothed arcs with which the pinions mesh in such manner as to be able to carry the arcs along.

The constant coincidence of the axis of the stabilizer with that of the pendulum proper 25 or vertical member 1 is assured by two stabilizing cylinders 19, exactly alike, which have been mentioned heretofore.

With the pendulum proper or vertical member there is connected (Fig. 2) in a 30 manner hereinbefore described, the hollow rod 38 of a cylindrical slide 39 for the distribution of compressed air, inside a piston 27 concentric with the slide and which follows the movements of the latter exactly. 35 Piston 27 moves inside the cylinder 28, called a stabilizing cylinder, whose axis (A—A) is also that of the piston and of the slide. This axis (A—A) is in a plane perpendicular to the axis of the tube 6 and may 40 rotate about axis (B—B) parallel to that of tube 6 and may meet, at a point 29, the axis of the pendulum 1. The slide 39 controls the piston 27 by means of compressed air, in the manner hereinafter described.

45 The compressed air arrives through the hollow rod 38 and passes to a duct 76 provided in the slide 39. This duct 76 communicates, when the piston moves inside the cylinder 28, with one of both ducts 77 or 78 provided 50 in the piston on each side of the axis A—A and directed in opposite directions to each other. The compressed air will so act on either side of the piston as to move it in a direction corresponding to the displacement 55 of the slide 27. The stabilizing cylinder 28 is connected to the vessel in the following manner. The points a' forming the ends of axis (a—a) about which the cylinder 28 freely rotates, forms part of a frame 30 which rotates freely itself about the axis (b—b), which crosses the axis (a—a) and is parallel to the axis of tube 6. When the vessel oscillates about the point of suspension 5 of the pendulum on pitching and 60 rolling about a momentary horizontal axis

of rotation, of any azimuth, passing through this point, the cylinder 19 oscillates about the axis (b—b) moving with the vessel, and the axes of the cylinder 19 and slide 39 pivots on the sleeve 31, which can turn on 70 the rod 3. It is therefore, evident that for very slight pitching and rolling angles the point of contact of the slide axis with the pendulum axis, is moved very little with respect to the latter, and the sleeve 31 75 scarcely oscillates on its axis. The axis c—c always remains perpendicular to the axis of the pendulum. Pistons 27 accurately follow the movement of the slides 39 in the cylinders 28.

80 When the vessel is immovable about the point of suspension the mounting of the device is such that the axes of the pendulum 1 and of the stabilizer coincide. The axes of the spindles or trundles of the sleeves 31 85 and 32, which substantially coincide when at rest, coincide still more accurately in operation, consequently the axis of the cylindrical rod 14 will thus have for a common point with the axis of the pendulum, that at which 90 the axis of the compressed air cylinder 28 meets said axis. In addition, as stated, the stabilizer carries a semi-spherical socket 17, by means of which it rests on the cupola 16. The stabilizer thus always has an axis passing 95 through point 5, and which having two points common with the axis of the pendulum, coincides exactly therewith.

The entire assemblage of the slide 39 and 100 its connection with the pendulum is balanced (Fig. 2) on the piston 27 and its connection with the stabilizer is balanced on the stabilizing cylinder 28 by a counterweight 37. As a constructional detail the slide is provided at its lower part with a 105 slight internal cavity where the full pressure of the compressed air may be exerted to relieve the weight and diminish friction in its very slight movements with respect to the piston. (Fig. 2).

110 As has been stated above, there are two identical constructions of stabilizing cylinders the axis (a¹—a¹) of the second cylinder is like that (a—a) of the first, perpendicular to the axis of the tube 6 bringing in the compressed air, but in an azimuth passing through this latter axis located at 90° from that of axis (a—a). The two azimuths will, for example, be 45° on each side of the vertical longitudinal plane of symmetry of the 120 vessel. The axis of the two cylinders are at a certain vertical distance from each other, the connections of the two slide rods with the pendulum being necessarily arranged in tiers one above the other. The pendulum 125 rotates freely about its axis.

In addition to the periods, generally oscillatory and which are slight with respect to those of the fluid, which are exerted on the pendulum-stabilizer by reason of its con- 130

nection with the pistons and slides of the stabilizing cylinders, during the entire period of operation of the device, the whole pendulum stabilizer may be further subjected to periods of magnitude, direction and duration, independent of the pitching and rolling movements, entirely contingent on and due to the inertia of the elements (pistons and slides) connected therewith and with the contingent obliquity of their rods. It is absolutely necessary that these kinds of movements be constantly neutralized.

It is to be noted that only the inertia of the slides is to be contended with, and not that of the pistons. The operation of the controlling of the pistons by the slides through compressed air combined with the 90° arrangement of the axes of the two cylinders of stabilization, brings back the force of inertia of the pistons to the axes (b-b), that is, to the vessel. For opposing the inertia of the slides, in accordance with the present invention, another assemblage 40 has been conceived to correspond with each assemblage 19 (Fig. 1) (cylinder, piston, slide and connections with the pendulum-stabilizer assemblage). In fact, if we assume that the vessel travels in a calm without pitching or rolling, at the moment at which the velocity will be increased, the slide will have found its force of inertia. The latter in any direction has a force according to the direction of the rod of this slide and a perpendicular force in this direction. The slide can only have the first of these forces by pulling on the pendulum rod. There is hence required a member of the same bulk as the slide symmetrical thereto with respect to the point of suspension of the device and connected to the pendulum at a point symmetrical to the point of attachment of the slide in order to neutralize the moment thus created. The stress of the force of inertia perpendicular to the direction of the rod will be provided during the inoperation of the apparatus, by the reaction of the vessel on the axis b-b which comprises the center of gravity of the slide, but during operation this center of gravity moves from the axis and the compensation for the moment thus created will be effected by the same arrangement as above, consequently this assemblage 40 shown in Fig. 6 will comprise a frame 43 pivoted about a vertical axis 44-45, connected to the vessel and arranged parallel to the pivotal axis b-b of the frame of the assemblage 19 with respect to the suspension point 5 of the pendulum. The stabilizing cylinder is replaced by a cage (or housing) 46 pivoted about the horizontal axis 47-48 arranged parallel to the pivotal axis (a-a) of the cylinder of assemblage 19. Housing 46 has vertical rollers 49 and horizontal rollers 50 between which a rod 51 having a bulk equal to that of the slide of assemblage 19 is

supported and guided. This rod is provided at one end with a fork 52 and a counter-weight 53, and at the other end with a fork 54 the arms of which are pivoted on pins (or trunnions) 41 fixed on the collar 42 centered on the axis of the pendulum and turning on rollers about the lower portion 11 of the bell of the pendulum. Each of the arms of the fork 54 terminate in two vertical lugs which bear on each side on two independent rollers 55-56 carried by the pins 41.

A result of the same assemblage 40 is to nullify the component of the weight of the slide along its rod on the pendulum.

When, after periods of inoperation, the compressed air being cut off, the device is again set in operation, the following conditions are to be fulfilled:

(1) The axis of the pendulum and the axis of the stabilizer must coincide exactly, so that the pistons and their slides will be in the relative position desired for service.

(2) It is necessary that the common line of these two axes coincides with the axis of tube 6.

(3) It is necessary that the vessel be rigid with respect to its center of gravity, that is to say, does not pitch nor roll, so that the device will have no preliminary angular deviation nor velocity with respect to its fixed operative position.

(4) The compressed air must be admitted before entering into operation, to assure immediate service.

These results are obtained:

(a) By locking together the pendulum 1 and the stabilizer for the periods of inoperation in a position in which their axes coincide exactly, and at the same time locking the assemblages with the vessel in such manner that said common axis coincides with the axis of tube 6 rigidly connected to the vessel.

(b) By unlocking only when the vessel is not moving about its center of gravity.

(c) By installing a safety device which prevents the release of the device, when the compressed air has not been previously admitted.

The locking and unlocking device is attached to a frame 57 see Fig. 7 rigidly attached to the vessel housing and protecting the apparatus, which may assume its various positions therein with respect to the vessel. This frame is interrupted in the regions of contact with the toothed arcs and the pinions and presents there openings for the escape of the air coming from the nozzles 10. Upon the frame 57 (Fig. 7) there is mounted an axle 58 supporting two pivotally mounted jaws 59-60, the ends of which may simultaneously grasp the rod 3 of the pendulum and tube 14 of the stabilizer. These two jaws extend beyond the axis 58 in the form of two slotted arms 61-62, the

slide blocks of which 63—64 are pivoted to nuts 65—66 mounted on a screw 67 having oppositely disposed threads and actuated by the crank 68. The manipulation of the jaws 5 59—60, which creates or destroys the coöperation of the pendulum and the stabilizer with each other and with the vessel, must not take place except when the air inlet is open. For this purpose the crank is provided with a fixed lug 69 which engages in a notch of the key which manipulates the air valve, when the latter is in the closed position, so that it will be necessary to open it to effect the release and likewise, it must 5 remain open to permit the locking.

When the vessel pitches and rolls, either while at a stand still or traveling at a speed too slow to cause the efficient operation of the ailerons (or blades), or if its movements are so slight as not to require moderation, it is of advantage to economize in the use of the compressed air consumed by the motors actuating the ailerons by disengaging these motors from the ailerons, the 5 stabilizing apparatus, however, remaining in operation. In accordance with the present invention, these clutching and releasing movements are effected when the pinion 25 is at the center of its toothed arc 24, since 0 at this moment the ailerons are no longer in engagement with the motors. It is sufficient to connect or disconnect the pinion 25 with or from the slide 75 of the motor which it controls. This is easily accomplished, as shown diagrammatically in Fig. 8, by causing pinion 25 to control a valve 71, which admits compressed air to the slide valve casing 72 of cylinder 73. The piston 74 of this cylinder has its rod connected to 10 one end of a lever 73¹, which is pivotally mounted at 73² and has its other end connected to the sliding portion of a clutch 73³. The other portion of this clutch is fixed to the pinion 25. The valve 71 will permit the 15 passage of the air only when the pinion 25 is at the center of the arc 24. The upper end of the lever 73¹ carries lug 81 which, when the clutch is disconnected, enters a lug 82 provided in the rotating slide 75 of 20 the motors which operate the ailerons.

When the vessel is stationary about its center of gravity, in calm fluids, the pendulum, balanced by the weight about its point of suspension 5, is maintained stationary, 25 and its axis is held in permanent coincidence with the axis of tube 6 as a result of the air blast from the nozzle 10. In agitated fluids, the pendulum is subjected to movements

arising from these blasts, coming from the crown (of air nozzles) which is subject to 60 movements, chiefly oscillatory, of the pitching and rolling vessel, and also to movement resulting from its connections with the remainder of the apparatus and with the vessel by its point of suspension, which, in 65 reality, has a certain extent. It is constructed in such manner as to have around the entire plane perpendicular to the axis of tube 6 passing through point 5, a moment of inertia sufficiently great to be subjected to oscillatory movements of only very slight amplitude, so that practically the same course 70 may be followed as in a period of calm. The stabilizer, which always follows the pendulum 1, by reason of the operation of the stabilizing cylinders, also keeps the same course, while as to the toothed arcs 23—24, the position of which is practically fixed, the oscillating vessel causes the rolling of the pinions 25, which control the operation 75 of the stabilizing ailerons of the vessel, on said arcs, the efforts exerted by these pinions on the stabilizer being further opposed by the compressed air of the stabilizing cylinders. 80

I claim:

An automatic stabilizing device to prevent pitching of vessels moving through fluids comprising a pendulum consisting of an indeformable revolution element, a stabilizer, two cylinders of stabilization connecting the pendulum to the stabilizer, two false cylinders symmetrical to these cylinders with respect to the point of suspension of the apparatus, pinions supported by the vessel, stabilizing ailerons having manipulating elements, toothed arcs attached to the stabilizer, engaging said pinions and controlling the elements for manipulating the surfaces of the stabilizing ailerons, a hollow rod rigidly attached to the vessel and on which the pendulum is suspended at its center of gravity, said rod conveying compressed air to the pendulum, a blast nozzle crown carried by said rod and located in a plane perpendicular to the axis of the rod, said crown uniformly distributing the compressed air on the inner circumference of the pendulum in such manner as to constantly urge the axis of the pendulum into coaxial relation 90 with the axis of the hollow rod. 95

In testimony whereof I affix my signature.
LOUIS ISIDORE HENRY.
